UNITED STATES PATENT OFFICE.

SYVER LOE, OF MINNEAPOLIS, MINNESOTA, ASSIGNOR TO LOE MULTIPLEX VOTING MACHINE COMPANY, OF MINNEAPOLIS, MINNESOTA, A CORPORATION OF MINNESOTA.

MULTIPLEX VOTING-MACHINE.

1,158,518.

Specification of Letters Patent.

Patented Nov. 2, 1915.

Application filed April 26, 1911, Serial No. 623,454. Renewed February 6, 1913. Serial No. 746,615.

To all whom it may concern:

Be it known that I, SYVER LOE, a citizen of the United States, residing at Minneapolis, in the county of Hennepin and State of Minnesota, have invented certain new and useful Improvements in Multiplex Voting-Machines; and I do hereby declare the following to be a full, clear, and exact description of the invention, such as will enable others skilled in the art to which it appertains to make and use the same.

My present invention relates particularly to multiplex voting machines and has for its especial object to improve that general type of multiplex voting machine disclosed and broadly claimed in my pending application S. N. 466,312, filed of date December 7th, 1908.

The invention consists of the novel devices and combinations of devices hereinafter described and defined in the claims.

In my present improved machine, as in the machine of my said prior pending application, I employ a common set of registers in combination with several independent sets of register actuators or keys and provide means whereby the common set of registers are moved in respect to the several sets of register actuators or vice versa, whereby the said common set of registers may be caused to co-act with any one of the said several sets of register actuators.

One improved feature of the present invention is directed to the provision of improved register actuators or keys and another feature is directed to the improvement in the means for rendering the set actuators operative on the said registers.

Various other important but novel features of the present machine over that of the machine of the prior application will appear in the following detail description, wherein like characters indicate like parts throughout the several views.

Referring to the drawings, Figure 1 is a perspective view showing the machine in use; Fig. 2 is a plan view of the machine, showing the same closed up and some parts being removed; Fig. 3 is a view corresponding to Fig. 2, but with different parts removed; Fig. 4 is a detail vertical section taken approximately on the line $x^4 x^4 c^2$ Fig. 3; Fig. 5 is an elevation of the parts shown

in Fig. 4, with some parts sectioned, on the line $x^5 x^5$ thereof; Fig. 6 is a fragmentary view in front elevation, showing a portion of the framework and certain of the register actuators and associated devices; Fig. 7 is a plan view, with parts broken away and some parts sectioned, showing the movable register support and one of the supplemental case sections or movable actuator supports; Fig. 8 is a vertical section taken approximately on the line $x^8 x^8$ of Fig. 7, some parts being broken away; Fig. 9 is a horizontal section taken approximately on the line $x^9 x^9$ of Fig. 8, some parts being broken away and some parts being removed; Fig. 10 is a fragmentary horizontal section taken approximately on the line $x^{10} x^{10}$ of Fig. 8, showing the parts on an enlarged scale; Fig. 11 is a vertical section taken approximately on the line $x^{11} x^{11}$ of Fig. 10; Fig. 12 is a fragmentary view in horizontal section taken approximately on the line $x^{12} x^{12}$ of Fig. 8, some parts being broken away; Fig. 13 is an elevation of the parts shown in Fig. 12, looking at the same from the outer side of the machine; Fig. 14 is a view chiefly in elevation, but partly in section, showing the parts illustrated in Fig. 12 and certain other parts, looking at the same from the inner side of the machine outward or in the direction of the arrow marked adjacent to Fig. 12, some parts being broken away; Fig. 15 is a view corresponding to Fig. 14 but showing certain of the parts in different positions and with some parts entirely removed; Fig. 16 is a fragmentary plan view of certain of the parts shown in Fig. 15, some parts being removed and some parts being broken away; Fig. 17 is a view corresponding to Fig. 11, but illustrating different positions of the parts and some parts being broken away; Figs. 18, 19, 20, 21 and 22 are detail views in plan, showing component parts of the register actuators; Fig. 23 is a fragmentary view showing a portion of one of the register locking bars; Fig. 24 is a detail view partly in vertical section and partly in elevation, illustrating a slightly modified construction of the register actuator support and lock hub guide; Fig. 25 is a view in elevation, with some parts broken away and some parts removed, showing the movable register supporting frame; Fig. 26 is

a detail section taken approximately on the line $x^{26} x^{29}$ of Fig. 25 and showing a register for recording the number of votes cast on the machine; Fig. 27 is a detail view partly in elevation and partly in vertical section, showing a vertically adjustable pedestal for the machine frame, some parts being broken away; and Fig. 28 is a horizontal section taken on the line $x^{28} x^{29}$ of Fig. 27.

10 In the machine illustrated in the drawings, the register actuators are assembled in three sets and are arranged in vertically and horizontally aligned rows, with finger pieces exposed for engagement at the outer portion 70 of a cylindrical case. Preferably and as shown, each set of register actuators is mounted on a hinged supplemental case section that is segmental in form and extends but little less than one-third the distance 75 around the case. The common set of registers in this preferred arrangement are assembled within the segment of an imaginary cylinder and are located inside of the cylindrical band of register actuators and are arranged to be moved into positions which will 80 subject the proper registers to the action of the corresponding members of any one of the three sets of register actuators. Also, as 85 illustrated, the register actuators, in vertical columns, are assigned for the voting of a so-called mixed ticket, that is, tickets on which the candidates of the different political parties are grouped together.

35 *Machine case and supports.*—A pedestal or rack which supports the case of the machine is, as shown, made up of a base spider 1 having three upright rods 2 rigidly secured thereto at their lower ends. As shown, the base spider 1 is supported by caster wheels 3. The framework of the machine case is 90 made up of a wheel-like base bracket 4 and wheel-like top bracket 5, the peripheral portions of the said two brackets being tied together by three upright tubular posts 6, in which the upper ends of the pedestal posts 2 are telescoped. An upright screw rod 7 is rigidly secured at its lower end to the hub of the pedestal base spider 1 and works loosely through the hub of the lower case bracket 4. The hub of the said base bracket 4 is supported by a bevel gear 8, the hub of which 95 works as a nut on the non-rotary screw rod 7. A ball bearing device 9 is interposed between the hubs of the gear 8 and of the said bracket 4. The entire machine case is adapted to be raised and lowered by rotary movements of the gear 8 on the screw rod 7; and this rotation of the said gear is adapted to be readily accomplished by a radial shaft 10 (see Figs. 8 and 9), mounted in suitable 100 bearings on the base bracket 4, provided at its inner end with a bevel pinion 11 that meshes with said gear 8 and provided at its outer end with an operating crank 12. The machine case will, of course, be raised when

the machine is arranged for operation, but may be lowered onto the pedestal spider 1 when out of use.

As already indicated, each of the three sets of register actuators is mounted on and carried by a movable segmental support that constitutes a part of the framework of the machine case. As shown, these independent segmental supports 13 are hinged to the case frame at 14 and each segmental support is made up of vertically spaced upper and lower plates rigidly tied together by suitable spacing posts, brackets and the like, the vertically spaced upper and lower portions of the said supports being tied together by reinforced upright partitions 15 and by channel-shaped ticket holders 16. The said ticket holders 16 are vertically extended but circumferentially spaced and they are adapted to detachably hold the tickets y (see particularly Fig. 6). When the segmental actuator supports 13 are swung outward, they afford ready access to the interior mechanism of the machine.

40 *Vote limiting mechanism.*—This mechanism may be, and preferably is, of the same construction as that disclosed in my said prior pending application and disclosed and broadly claimed in my prior patent No. 712,079, of date October 28, 1902, entitled 95 "Voting machine" and, hence, in this case is illustrated only in part.

45 For each vertical column of register actuators, there is a vertical column of laterally expandable devices made up of threaded hubs 17 and external nut members 18 (see Fig. 10). The so-called hub members 17 of each stack are aligned axially and are mounted to slide axially upward and downward on a fixed non-rotary shaft 19, preferably formed 105 with a longitudinal keyway, for the reception of key lugs on the said nut members. At their upper and lower ends, the several non-rotary shafts 19 are rigidly secured to the upper and lower portions of the hinged 110 segmental supports 13. The nut members 18 are provided with external teeth and they are mounted to rotate within upright tubular casings 20 that are fixed to the upper and lower portions of the hinged supports 13 115 and are cut away at their backs, as shown at 20^a (see Figs. 10 and 17) for a purpose which will hereinafter appear. In the modified construction illustrated in Fig. 24, the 120 said nut members 18 work through sleeve-like hubs of brackets 21 secured to an upright supporting bar 22, which latter will be rigidly secured at its upper and lower ends to the upper and lower portions of the appropriate hinged supports 13.

50 *Register actuators.*—The register actuators or keys, which as before stated, are arranged in vertical columns and horizontal rows, in the present machine involve novel 125 and important features, the preferred ar-

65

angement of which will now be described in detail. In each of the three sets of register actuators, there is an actuator for each register and the common set of registers.

- 5 Each register actuator comprises a register operating lever 23 and a finger lever or key 24. The said levers 23 are intermediately pivoted on the respective tubular casings 20 and are supported on shelves 25 secured to said tubes. The key levers 24 are intermediately pivoted on upright shafts 26 located just opposite each shaft 19 and mounted for oscillatory movements in the upper and lower portions of the corresponding hinge supports 13. The outer ends of the pivoted key levers 24 work through slots of a thin plate 27, which is suitably secured to the partitions 15 and ticket holders 16 of the hinge supports 13 and they are located in a horizontal line with the names of the candidates on the tickets to which they are assigned. Normally, they extend radially outward in respect to the machine case and when operated, they are turned directly over the printed name of the candidate to whom they are assigned. The outer end of each lever 23 is provided with a long slot 28 that engages a pin 29 carried by the inner end of the key lever 24. Each key lever 24 rests upon a so-called actuator restoring arm 30 that is rigidly secured to the corresponding shaft 26, preferably, by a key and coöperating supporting pin. The inner end of each key lever 24 is provided with a depending pin 31, which coöperates with the restoring arm 30 in a manner hereinafter described.

Resting directly on top of each register actuator lever 23 is a similar lever 32 provided with an extended arm having a slot 33 that is also engaged by the pin 29 of the key lever 24. The slots 28 and 33 of the levers 23 and 32 intersect each other at an angle, whereby a peculiar and important movement, hereinafter described, is produced. The levers 32 are also rotatively mounted upon the corresponding casings 20 and they are adjustably connected each to a corresponding nut member or gear 18 of the lock limiting mechanism. Preferably, this adjustable connection between the said levers 32 and nut members or gears 18 is accomplished by a ring 34 having a tooth 35 engaging teeth of the said gear and having a depending pin 36 that engages the inner extremity of the slot 33. When the ring 34 is connected to the gear 18 and lever 32, as best shown in Fig. 10, the said lever 32 is connected for rotation or oscillation with the said gear. When it is desired to readjust the nut members or gears 18, the ring 34 is lifted far enough to disengage its pin 36 from the slot 33, and there is sufficient play within the said ring and casing to permit the tooth 35 to be disengaged from the teeth of the said gear and reengaged with

other teeth thereof, thereby permitting the proper re-adjustment for different elections.

In the construction illustrated in Fig. 24, the levers 23 and 32 and the ring 34, instead of being mounted on a complete casing tube, 70 are mounted on the tubular hubs of the brackets 21.

Registers and support for same.—The registers or tallies are arranged in vertical columns and horizontal rows corresponding 75 to the arrangement of the levers 23 in the several sets of register actuators. These registers or tallies may be of any suitable or standard construction and they are preferably arranged to be directly actuated by an escapement mechanism of the character disclosed and claimed in my prior Patent 804,962 of date November 21, 1905, entitled "Voting machine." Substantially the same registers and escapement devices herein employed are also disclosed in my said prior application S. N. 466,312, but the present invention involves not only an improved arrangement of the register actuators but also an improved or modified arrangement for 80 rendering the said actuators operative on the said registers through the said escapement devices. The said registers are indicated as entireties by the numeral 37 and are shown as provided with dove-tail projections 38 (see Figs. 11 and 17) that fit dove-tail seats of vertical supporting bars 39. The unit number of each register is connected to move with the pin wheel 40 that is provided with ten laterally projecting cam 95 pins. For coöperation with each escapement wheel 40, there is provided an escapement lever 41 that is pivoted at one end to a projection of the corresponding register keys and, at its intermediate portion, is provided with a laterally projecting escapement head or block 42, the ends of which are reversely beveled, so that the escapement wheel 40 will be given a one-half step or unit of rotation under downward movement of the lever 41 100 and a second one-half step or unit of rotation under upward movement of the said lever.

The number of register supporting bars 39, as well as the number of registers on 115 each bar, may, of course, be varied, but the total number of registers should, however, correspond to the number of register actuators or keys in any one of the several sets. As shown, these register supporting bars 39 120 form vertically extended members of a supplemental register supporting frame made up of the said bars and of upper and lower segmental brackets 43. The extremities of these brackets 43 are formed with hubs that 125 slide vertically upon upright posts 44 of a main register supporting frame made up chiefly of the said posts 44 and of upper and lower spider-like wheels or heads 45. The hubs of these wheels 45 are rigidly secured 130

to a tubular upright central spindle 46, into which the upper end of the screw rod 7, already noted, is telescoped. The upper end of the said tubular spindle 46 is relatively mounted in the hub 47 of the fixed top frame bracket 5. Secured to the spindle 46, just below the said hub 47, is a bevel gear 48 that meshes with a bevel pinion 49 secured to the inner end of a radial shaft 50 journalized in suitable bearings on the said top bracket 5 and provided, at its outer end, outside of the machine case, with an operating crank 51. The gear 48 has three times as many teeth as the pinion 49, so that three complete rotations of the shaft 50 are required to impart one complete rotation to the spindle 46 and register supporting frame carried thereby. From this it follows that one complete rotation of the crank 51 will suffice to oscillate the registers from a position in which they are arranged for coöperation with one set of register actuators into a position in which they will co-operate with another or adjacent set of register actuators. To accurately position the rotary main register frame in any one of the said three positions, the operating crank or lever 51 is shown as provided with a spring-pressed lock plunger 52, the end of which is adapted to be inserted through a perforation or seat in a lock disk 53 (see Figs. 4 and 5), which latter is rigidly secured to the top frame bracket 5.

The ball bearing device 54 is preferably interposed between the hubs of the lower brackets 4 and 45 of the machine case and of the main register carrying frame (see particularly Fig. 8). A long radially extended pointer or indicating finger 55 is secured to the extreme upper end of the spindle 46, for a purpose which will hereinafter more fully appear. It should be here noted that the free ends of the register escapement levers 41 work through vertical slots 56 of vertically extended lock strips 57 secured at their upper and lower ends to the upper and lower brackets 45 of the main register carrying frame. The two-fold purpose of this so-called lock strip will appear later on.

The registers so far noted are for the purpose of registering the individual votes cast for the various candidates. As an independent or auxiliary device, I provide a register which will record the total number of voters who will cast their votes by the use of the machine. This register is just like the other registers described and it is indicated as an entirety in Figs. 25 and 26, by the numeral 57^a. Its frame is shown as secured to the top frame bracket 45 and its escapement lever 41^a works through a quite closely fitting perforation in one of the lock strips 57 (see Fig. 26).

The segmental supplemental register sup-

port, made up of the bars 39 and brackets 43, is mounted for slight vertical movements on the posts 44 and the vertical movements thereof are controlled by a connecting rod 58 pivotally attached, at its lower end, to the bracket 43 and pivotally attached at its upper end to the wrist pin of a crank disk 59 secured to the inner end of a short shaft 60, journaled in a bearing 61 on the upper wheel or spider 45 of the main rotary register support. At its front end, the shaft 60 is provided with a spur gear 62 (see particularly Figs. 8, 14, 15 and 25). Normally, the crank disk 59 is locked in the position best shown in Fig. 8 (in which position the supplemental register supporting frame is raised), by means of a lock lever 63 intermediately pivoted to and working in a slot formed in the bearing 61 and in the overlying peripheral portion of the upper wheel bracket 45. It should be here noted that the said upper wheel bracket 45 of the main register supporting frame is provided with a peripheral groove 64 and that the lock lever 63, at its outer end, has a bifurcated head 65, the notch of which normally alines with the said endless peripheral groove 64. A secondary or permanent lock is also provided for securing the lock lever 63 in its locking position, shown in Fig. 8, after the casting of votes at the election has been completed. This secondary or permanent lock is, as shown, in the form of a lock lever 66 intermediately pivoted to the upper segmental bracket 43 and pivotally attached, at its inner end, to an operating bar 67 slidably mounted on the said upper bracket 43. When the lever 66 is in an operative position, its outer end overlies the inner end of the lock lever 63. The operating bar 67 is adapted to be held in position to hold the lever 66 engaged with the lock lever 63, by means of a padlock or any other suitable key-actuated lock, not shown. When the machine is put into condition for use at an election, the secondary lock lever 66 will, of course, be moved so that its outer end will be thrown to one side of the inner end of the said lock lever 63. The operation of this mechanism will be presently explained.

Voter's operating crank and coöoperating parts.—In connection with each set of register actuators or in connection with what might be designated as each key board, I provide a voter's operating crank, indicated by the numeral 68, which is exposed at the upper front portion of the corresponding hinged or segmental actuator support 13. These operating cranks 68 are secured to the outer ends of the radially extended shafts 69 journaled in outer bearings 70 and inner bearings 71 (see particularly Figs. 3, 8, 12, 13, 14 and 15). The outer bearings 70 are pivoted to the upper portions of the corresponding supports 13 and the inner bearings 71 are carried each

by one arm of a bell crank 72 and work in vertical slots formed in guide brackets 73 secured to the upper portion of the corresponding support 13. The bell cranks 72 are pivoted to the bearing brackets 73, at 74, and their upper arms are connected to independently movable bars 75 mounted for endwise sliding movements on the top plates of the respective supports 13.

10 The inner ends of the shafts 69 of the operating cranks 68 are preferably slightly reduced in diameter and they are arranged to work in the peripheral groove 64 which, as already stated, is formed in the upper 15 wheel or bracket 45 of the main register support. Also, these reduced inner ends 69^a of the said shafts 69 are of such diameter that when moved into the notched outer end or head 65 of the lock lever 63, they may 20 be, one at a time, oscillated downward in the seat or notch 64^a (see Fig. 25), which is formed in the said upper wheel 45 and transversely intersects the peripheral groove 64.

25 Adjacent to the reduced inner ends, the said shafts 69 are provided with spur gears 76. These gears 76 are so located that they are adapted to be engaged, one at a time, with the gears 62, as will hereinafter more 30 fully appear. At their intermediate portions, the shafts 69 are provided with ratchet wheels 77 and with segmental gears 78. The segmental gears 78 coöperate with segmental rack bars 79 carried by segmental 35 push bars 80 mounted for endwise sliding movements in suitable bearings provided on the lower plate of the top portion of the support 13. These push bars 80 are independently movable on the respective supports 13 and they are independently connected each to the upright rock shafts 26 of the corresponding key board or set of 40 register actuators. This connection is preferably made (see particularly Figs. 8, 12 and 16), by means of arms 81 secured to the extreme upper ends of shafts 26 and having heads that engage notches 82 formed in the coöperating push bar 80.

Each of the three independent ratchet 50 wheels 77 is provided with a peripheral lock notch 77^a that is adapted to be engaged by a lock lug 83 on the long arm of a three-armed lever 84 pivoted at 84^a to a bearing bracket 85 secured on the top of 55 the corresponding support 13. The depending arm of the said lever 84 is adapted to be engaged by a pin lug 86 on the underlying coöperating push bar 80, and the upper arm of said lever 84 is provided with a pin 60 87. Pivotal mounted on the hub 47 of the top frame bracket 5 are two sets of three levers each, one set being indicated by the characters a^1 , a^2 and a^3 and the other set being indicated by the characters b^1 , b^2 and b^3 . 65 The longest arms of the three levers a^1 , a^2

and a^3 directly overlie each other and extend outward through slots 88 in the lock disk 53 (see particularly Figs. 3, 4 and 5), terminate outside of the case in finger pieces a and are adapted to be engaged with either 70 of the two notched extremities of the said slots. The shorter arms of said levers a^1 , a^2 and a^3 are shown as bifurcated and engaged with depending pins 89 of the appropriate members of the three slides 75. The 75 long arms of the levers b^1 , b^2 and b^3 extend outward through slots 90 in the said disk 53 and terminate in suitable finger pieces, while the short arms of the said three levers are shown as coupled to pins 87 secured on 80 the upper arms of the respective lock pawls 84. The extreme downward movement of the pawls 84 is limited by stop pins 91, shown as secured to the brackets 85.

In connection with each key board or set 85 of register actuators, a voting booth is provided and, as shown, each voting booth is made up of a pair of wings 92 and curtains 93 supported therefrom by rods 94. The wings 92 are preferably of the arrangement 90 disclosed in my said pending application. These booth forming devices are briefly shown in Fig. 1 only.

For indicating to the attendant of the machine or the election judge when a voter in 95 any one of the booths has completed the setting of the keys representing his vote, a signaling device is provided. This signaling device is preferably in the form of a pivoted arm 95 located one in each booth and suitably pivoted at 96 to the upper portion of 100 the corresponding actuator support 13 and provided with a projecting lug 97 that is adapted to be engaged by the voter's operating lever 68, as hereinafter more fully described. Movements of the operating lever 68 are limited by a stop 98 (see Fig. 13) secured on the upper portion of the corresponding support 13 and it may be here stated that the gear 76 is of such greater 110 diameter than the gear 62, that movement imparted to the former when the lever 68 is moved from one extreme position to another against the stop 98, while the said gears are engaged, the said gear 62 will be 115 given just one complete rotation, to-wit, from the position shown in Fig. 8 back again into the same position.

Register re-setting device.—Attention is here particularly called to Figs. 8 and 10. 120 In applying the improved register re-setting device, for setting the registers back to zero, after the election is over, or in preparing the machine for an election, the pin wheels 40, which are attached to the unit 125 members of the registers, are provided with a toothed hub 99 that is adapted to be engaged by a flexible strap 100 attached at one end to a spring-wound drum 101 which, as shown, is journaled to a bracket 102 having 130

6

a split sleeve that is frictionally clamped on the tubular spindles 46, so that the said bracket may be adjusted vertically and rotated in any desired position. It will, of course, be understood that the registers may be set to zero by rotation of tooth hubs 99. Rotation of the tooth hubs may be readily accomplished by drawing the strap 100 over the same in tight frictional engagement therewith.

Operation.—As preliminary to arranging the machine for action, the secondary or permanent lock lever 66 (see Figs. 7 and 8), should be moved pivotally into an inoperative position shown by dotted lines in Fig. 7. This releases the primary lock lever 63 so that the machine may be thereafter used. Normally, the gear 76 on the shaft of the voter's operating lever 68 is held in its raised or inoperative position by engagement of the inner end of the shaft 69 with the peripheral groove 64 in the upper head 45 of the oscillatory or rotary register carrier, and the said gear and all of the parts carried by the said shaft 69 are normally locked against rotation by the engagement of the lock lug 83 of the three-armed lever 84 (see Fig. 14), with the notch 77^a of the ratchet wheel 77. Figs. 8, 12, 13, 14, 15 and 16 show positions of the voter's operating crank 68 and associated parts when the machine is in such condition that three voters in the three different booths may simultaneously, or individually, but absolutely independently set the various keys or register actuators which represent the vote that he wishes to cast. Attention is here particularly directed to Fig. 10 wherein the normal condition of one of the register actuators is indicated at the left and the condition thereof when moved to represent a vote is indicated at the right. Normally, it will be seen that the key lever 24 of its actuator projects radially outward and that it is moved into an operative or set position by moving the same pivotally to the left so that it will stand directly over the candidate's name on the ticket *y*, to which it is assigned. When the key lever 24 is moved from its normal to its set or operative position, as stated, its pin 29, during about the first half of such movement, moves longitudinally in the slot 28 of the lever 23 and the latter lever is given very little, if any, movement but the said pin 29 moves at an angle to the slot 33 of the coöperating lever 32 which, it will be remembered, is coupled to and operates the coöperating lock nut member 18, and hence, during the first half of the noted movement of said lever 24, the coöperating vote limiting device made up of hubs 17 and nut members 18, will be set. Approximately the last half of the movement of the lever 24 from its normal to its set position, moves the lever 23 into its inwardly projected set or opera-

tive position shown at the right in Fig. 10, and while this movement is being imparted to the said lever 23, the pin 29 moves longitudinally in the slot 33 of the lever 32, as shown at the right of Fig. 10, and the said lever 32 remains stationary during such time. Otherwise stated, the said movement of the lever 24 first sets the vote limiting mechanism and thereafter moves the register actuating lever 23 into its inwardly projected set or operative position. When the voter in any one of the booths has completed the setting of the keys representing his entire vote, he turns upward the segmental arm 95 which is marked with the number of the booth which he occupies, and then the attendant of the machine, by turning the crank 51, rotates the register carrying frame until the pointer 55 is radially alined with the upturned segmental arm 95. It will here be remembered that one rotation of the crank 53 is just sufficient to impart $\frac{1}{3}$ rotation to the register support, and when the lever 51 is in its normal position shown in Figs. 4 and 5, the common set of registers carried by the said register support will be positioned for coöperation with the set register actuating levers 23 of one or the other of the booths, and the bifurcated head of the lock lever 63 will then embrace the inner end of the operating crank shaft 69 of that booth. As shown in Figs. 8 and 25, when the registers are thus positioned in respect to the set actuators of the particular booth, the voter's operating crank is still locked, as shown in Fig. 14, by engagement of the lug 83 of the lever 84 with the notch 77^a of the ratchet wheel 77. Hence, before the voter can register his vote represented by the actuators which he has set, the attendant of the machine, by a movement of the proper one of the levers a^1 , a^2 , or a^3 , as the case may be, must cause the corresponding bell crank 72 to oscillate on its pivotal support 74 and thereby lower the coöperating gear 76 into engagement with the then underlying gear 62 which is carried by the register support and controls the vertical movements of the registers. When the said gear wheels 76 and 62 are engaged, as shown in Fig. 15, the notch 77^a of the ratchet wheel 77 is lowered from engagement with the lock lug 83, but the said lock lug is still in position for action on the teeth of the said ratchet wheel. Hence, now the voter may move his operating crank 68 from the position shown by full lines in Fig. 13 into the position shown by dotted lines in the same view. It should be here further stated that when the gear 76 was moved downward into mesh with the gear 62, the lock lever 63 was raised out of engagement of the notch of the crank disk 55 thereby releasing the latter.

During approximately the first half of the movement of the voter's operating lever 68

from its full line to its dotted line position in Fig. 13, the segmental gear 78 is not thrown into action on the coöperating rack 79, but during this first half of the said lever 5 movement, the crank disk 59, through the intermediate gears 76 and 62, is given one half rotation thereby throwing the vertically movable register supporting frame 43 downward carrying with it all the registers. Under this downward movement of the registers, the projecting ends of the register escapement levers 41 are thrown onto such of the register actuating levers 23 as have been set or moved into operative positions (see 15 particularly Fig. 11). The upward movement thus imparted to the escapement levers 41 thus engaged, will impart one-half step of movement to the unit member of each coöperating register. The second half step of 20 the movement will be imparted to the unit members of the registers when the said levers 41 are again forced downward, and such movements are insured by engagement of the said levers 41 with the upper extremities 25 of the slots 56 of the lock strips 57 (see Fig. 17).

The second half of the movement of the operator's lever 68 from the position shown by full lines into the position indicated by 30 dotted lines in Fig. 13, accomplishes the following several operations, to-wit: It turns the crank disk 59 back to its normal position and again raises the register frame 43 and the registers. It causes the segmental 35 gear 78 to engage the rack 79 and thereby move the same and the bar 80 toward the left in respect to Figs. 12 and 13, or toward the right in respect to Figs. 14, 15 and 16. When the bar 80 is moved, as just stated, it operates 40 on the arms 81 of the vertical rock shaft 26 and causes the arm 30 of the latter to engage the pins 31 of the key levers 24 and thereby restore all parts of the register actuators and of the coöperating vote limiting devices 45 to normal positions. Attention is here called to the fact that under movement of the operator's lever 68 from its full line to its dotted line position in Fig. 13, the lug 83 of the lever 84 which is then released from the notch 50 77^a, operates as a retaining pawl to prevent backward or reverse movement of the said lever 68 so that the said lever 68 cannot be moved from its dotted line position back to its full line position until the said lug 83 is raised by movement of the lever 84 into a position slightly higher than shown in Fig. 15. To effect such movement of the lever 84, the machine attendant must move the proper one 55 of the three levers b^1 , b^2 , or b^3 , as the case 60 may be, and this being done, the voter's operating lever 68 may be then oscillated back to the full line position shown in Fig. 13. This return movement of the said operating lever 68 should be accomplished by the voter as 65 the first operation upon entering the booth

and before he has set the register actuators representing his vote.

There is assumed to be sufficient frictional engagement between the levers b^1 , b^2 and b^3 and their guide slots 90 to yieldingly hold 70 the same in whichever position they may be set. When the bar 80 was moved from the right toward the left, or into the position shown by full lines in Fig. 14, which movement is accomplished by movement of the operator's lever 68 from its dotted line position into its full line position in Fig. 13, the pin 86 on the said bar 80 strikes the independent arm of the lever 84 and thereby restores the particular lever b^1 , b^2 or b^3 to its 75 normal position and insures the reengagement of the lock lug 83 with the notch 77^a of the ratchet wheel 77 as soon as the gear 76 is again raised out of engagement with the gear 62. When the said gear 76 is raised out of engagement with the gear 62, the lock lever 63 again drops into the notch of the crank disk 59 (see Figs. 7 and 8) and locks the latter against rotation, with the register frame 43 and the registers carried thereby 80 in their normal raised positions. This engagement or raising movement of the gear 76 necessary to accomplish the results, just stated, is produced by the machine attendant when he restores the normal position to 85 particular lever a^1 , a^2 or a^3 which was operated to throw the said gear 76 downward into mesh with the said gear 62. When the said parts have been restored to their normal 90 positions, as just stated, the inner end of the operator's crank shaft 69 is again alined with the peripheral groove 64 in the upper head of the register support, and the said register support may then be rotated into any other of its positions with its registers 95 located for coöperation with the actuators of any one of the other booths.

What I claim is:

1. In a voting machine, the combination with a set of registers and a movable support therefor, of a coöperating set of register actuators and vote limiting mechanism coöperating with the latter, a crank with connections for reciprocating said register support, a lock for the latter, register restoring devices, a voter's operating crank, and means operative by an attendant, for rendering the said voter's operating crank operative to release said lock, to rotate said crank which is normally held by said lock 110 115 and to render the said voter's operating crank operative on said actuator restoring devices.

2. In a voting machine, the combination with a set of registers and a support therefor, of register actuators and coöperating vote limiting mechanism, a crank with connection supporting said register support, a primary lock normally holding said crank against movement, and a secondary lock for 120 125 130

securing the said primary lock in an operative position, to thereby lock the machine in an in-operative position.

3. In a voting machine, the combination with a set of registers and a vertically movable support therefor, of a crank shaft provided with a gear and with a notched crank disk, a connection between said crank disk and said register support for moving the latter, a lock lever normally holding said notched crank disk against rotation with said register support raised, a set of register actuators and coöperating vote limiting devices, a voter's operating crank operative on said lock lever and having a gear normally out of mesh with the gear of said crank shaft, and means operative by an attendant for rendering said voter's operating crank operative to release said lock lever and to move the gear thereof into mesh with the gear of said crank shaft.

4. In a voting machine, the combination with a set of registers, of a coöperating set of register actuators, and vote limiting devices comprising hub and nut members having threaded engagement, each of said register actuators comprising a register actuating lever and a finger operating lever, the said finger operating lever being arranged to set the coöperating vote limiting devices under a part of its movement and to move the said register actuating lever during another part of its movement.

5. In a voting machine, the combination with a set of registers, of a coöperating set of register actuators and vote limiting mechanism comprising a hub and nut members having threaded engagement, and slotted arms connected to the said nut members, each of said register actuators comprising a register actuating lever and a finger operative lever, the former having an arm with a slot that extends at an angle to the slot in the arm of the said coöperating vote limiting nut member, and the said finger operating lever having a cam pin or projection that works in the slot of the said arm and lever, substantially as described.

6. In a multiplex voting machine, the combination with several sets of register actuators, of a common set of registers and a movable support therefor, means for moving said register support to position said registers for co-action with any of said group of actuators, and means for moving said register support and the registers carried thereby, to cause the set actuators, while in set positions, to operate corresponding registers.

60 7. In a multiplex voting machine, the combination with several sets of register actuators, of a common set of registers and a movable support therefor, means for moving said register support to position said registers for co-action with any of said sets

of actuators, and means for imparting another movement to said register support, to cause the set actuators to operate corresponding registers.

8. In a multiplex voting machine, the combination with several sets of register actuators, of a common set of registers and a movable support therefor, means under the control of an attendant for moving said register support to position said registers for co-action with any of the said sets of actuators, a voter's operating shaft for each set of actuators, a crank with connections for moving the register support so as to subject the registers to corresponding set actuators, and means carried by said register support and operative to hold the several voter's operating shafts in inoperative positions and to permit the same to be connected to said crank shaft, one at a time, and only when the registers are positioned for co-action with the actuators of the corresponding sets.

9. In a multiplex voting machine, the combination with a rotary main register support and a supplemental vertically movable register support carried thereby, of a set of registers mounted on said supplemental support, several independent sets of register actuators and coöperating vote limiting devices, means for rotating said main register support to position said registers for coaction with any of said sets of actuators, a crank shaft carried by said rotary main support and provided with a gear, a crank connecting said supplemental support to said crank shaft, a lock for said crank shaft, a voter's operating crank associated with each set of actuators and provided with a gear, and an annular member carried by said main register support and operative on the shaft of said voter's operating crank, normally to hold the gear thereof in an inoperative position but arranged to couple the shaft of said voter's operating crank, one at a time, to the said crank shaft lock and to permit the corresponding gear to be engaged with the gear of said crank shaft, substantially as described.

10. In a voting machine, the combination with a set of registers and a movable support therefor, of a set of register actuators and coöperating vote limiting devices, means including a gear for moving said register support, a voter's operating shaft having a gear normally out of engagement with the first noted gear, and means for engaging the said gears, substantially as described.

11. In a voting machine, the combination with a set of registers and a movable support therefor, of a set of register actuators and coöperating limiting devices, means including a gear for moving said register support, a lock for said gear, a voter's operating shaft having a gear normally out of mesh

with the first noted gear, and means for releasing said lock and for engaging the said two gears, substantially as described.

12. In a multiplex voting machine, the combination with a main register support and a supplemental support movable thereon, of a crank shaft carried by said main support and provided with a gear, a connection between said crank shaft and said supplemental frame for moving the same, a lock for said gear and crank shaft, several independent sets of register actuators and coöperating vote limiting devices, means for moving said main support to position said registers for co-action with any one of the said sets of actuators, a vote operating shaft associated with each set of actuators and provided with a gear, and means for engaging the gear of said crank shaft with the gear of the voter's operating shaft with which it is alined, and means for releasing said lock when said gears are engaged.

13. In a voting machine, the combination with a set of registers, of a coöperating set of register actuators and vote limiting devices, each of said register actuators comprising a pair of pivoted members, the one having a cam action on the other, one thereof being arranged to set the coöperating vote limiting devices under a part of its movement and to move the other member into a set position under a part of its movement.

14. In a voting machine, the combination with a set of registers, of a coöperating set of register actuators and vote limiting devices, each of said register actuators comprising a register actuating lever and a finger operated lever, said finger operated lever being arranged to set the coöperating vote limiting devices under a part of its movement and to move said register actuating lever during another part of its movement.

15. In a voting machine, the combination with a set of registers, of a coöperating set of register actuators and vote limiting mechanism for the latter, means for restoring said actuators to normal positions, and means independent of said actuator restor-

ing means for moving said registers, as a group, to thereby cause the set actuators to operate corresponding registers while they are in their set positions.

16. In a multiplex voting machine, the combination with a set of registers, of several independent sets of register actuators for action on said common set of registers, means for moving one of said class of elements bodily to thereby bring said common set of registers into coöperative relation in respect to any one of said sets of register actuators, and means for imparting another movement bodily to one of said class of elements to thereby cause the set actuators, while in set positions, to actuate corresponding registers.

17. In a multiplex voting machine, the combination with several independent sets of actuators, of a register support, a common set of registers carried by said support, and means for moving said register support both vertically and horizontally to render said registers subject to the set members of any one of said independent sets of register actuators, and one of the said movements serving to cause said actuators, while in their set positions, to actuate corresponding registers.

18. In a multiplex voting machine, the combination with circumferentially spaced register actuators arranged in several independent sets, of a common set of registers circumferentially spaced and contained in the space surrounded by said several sets of register actuators and arranged to be moved pivotally and vertically into position for co-action with any one of said independent sets of register actuators, the vertical movement thereof serving to cause said actuators, while in set positions, to actuate corresponding registers.

In testimony whereof I affix my signature in presence of two witnesses.

SYVER LOE.
